UNITED STATES PATENT OFFICE.

CHARLES VAN AMBURGH, OF LONG BEACH, CALIFORNIA.

FLUID PUMP.

Application filed May 15, 1924. Serial No. 713,493

My invention relates to fluid pumps and particularly, although not necessarily, to oil well pumps.

The purposes of my invention are to provide a fluid pump which is removably associated with an oil string casing to permit its withdrawal without disturbing the casing; a pump which is operable to elevate fluid in such manner that resultant settling chambers are formed and permanently maintained between the pistons and the fluid elevated which function to prevent solid particles from entering the working area of the pistons, whereby the pistons and cylinder walls are maintained free from the abrasive action of sand or other solid particles; a pump in which the resultant settling chambers are adapted to be filled by the oil handled and in such manner that bodies of oil are permanently interposed between the pump pistons and the oil pumps or elevated to move bodily with the pistons in permitting the latter to properly function in elevating the oil and so that should they contain solid particles in suspension, such as sand, shale or the like, the solid particles will be given ample opportunity to settle to the bottom of the bodies and be ultimately discharged from the pump, thereby presenting between the pistons and the contaminated oil elevated, fluid mediums which are clean and free from solid particles and which operate to maintain the pistons and cylinder walls free of the solid particles with the ultimate and primary object of reducing to a minimum the wear of the pistons and cylinders; a pump which, in its application to an oil string casing, is capable of being filled by the uppermost strata of oil in the casing or that strata which is free from solid particles so that the interposed fluid mediums above described are initially and permanently clean; a pump in which the oil elevated and containing solid matter in suspension is raised in the same ratio as received from the well, thus preventing the accumulation of foreign matter in the pump and eliminating the periodical cleaning operations necessary in pumps heretofore proposed; a pump which is double acting so that the column of oil elevated moves at half the velocity of that elevated by single acting pumps, thereby greatly reducing the resultant shocks and vibrations; and a pump which is capable of being rotated in the oil string casing to enable positive seating and

thus provide a fluid-tight connection between the pump and casing, and capable of being elevated from its seat so as to allow the oil in the casing above the normal oil level to run back and thus flush out any solid matter which may have accumulated in the pump below the barrel owing to inactivity of the pump, so that the pump can be properly reseated.

I will describe only one form of fluid pump embodying my invention, and will then point out the novel features thereof in claims.

In the accompanying drawings

Figure 1 is a view showing in vertical section one form of fluid pump embodying my invention in applied position within an oil string casing;

Figure 2 is a view similar to Figure 1, but with the pistons of the pump in the opposite extreme positions from those shown in Figure 1;

Figures 3, 4 and 5 are transverse sectional views taken on the lines 3—3, 4—4 and 5—5, respectively, of Figure 1.

Referring specifically to the drawings, in which similar reference characters refer to similar parts, my invention in its present embodiment is shown as applied to a conventional form of oil string casing, such casing including an upper section 15 and a lower section 16 connected by a threaded collar 17. The fluid pump forming the subject matter of my invention includes a seat or supporting member 18 which is adapted to be fixedly secured in spanning relation within the casing by interposing the same between the confronting ends of the sections 15 and 16 in a manner clearly illustrated in Figures 1 and 2. This seat or supporting member 18 is provided with an axial opening 19 through which oil is adapted to be drawn upwardly by means of the pump embodying my invention. This member 18 serves as a supporting means for the entire pump, which latter is adapted to be lowered into the casing until it rests upon such member.

The pump comprises a working barrel including a lower cylinder 20 and an upper cylinder 21 arranged with its lower end within the lower cylinder 20 and suitably secured thereto. The lower end of the cylinder 20 is threadedly connected to a valve body 22 through the medium of an exteriorly threaded collar 23, and this valve body

carries a valve seat 24 which is threadedly fitted in the lower end of the valve body, as clearly shown in the drawings. The valve seat 24 is formed with a beveled edge 24^a which has a ground joint with a beveled edge 17^a of the seat member 18, it being noted that both of such edges are beveled. This member 24 provides a seat for a ball valve 25 which constitutes an intake valve 10 in that in its unseated position as shown in Figure 2 the influx of oil from below the member 18 into the valve body is permitted. To allow the oil to circulate into the connecting collar 23 and ultimately into the lower cylinder 20, the valve is maintained against seating upon the lower end of the collar by fingers 26 formed on and depending from the lower end of the collar. In the seated position of the valve 25, as shown in Figure 20 1, it reposes upon a relatively sharp edge 27 of the valve seat 24, and in this position of the valve it will not discharge oil downwardly into the port 19. As clearly shown in Figure 5, the valve body 22 is provided with a circular series of vertically disposed discharge ports 28. Each port is controlled by a ball valve 29 in such manner that oil can flow only upwardly through the ports, the valves gravitating to closed position should 30 oil attempt to move downwardly through the ports. To limit the upward movement of the valves 29 and to insure their proper seating upon seats 30, a valve cage 31 is secured to the connecting collar 23 in the manner shown. The seats 30 for the valves 29 are formed with relatively sharp edges in the same manner as the edge 27 and for the purpose of reducing the possibility of solid matter contained in the oil to be elevated 35 40 lodging between the seats and valves.

Reciprocable within the barrels 20 and 21 are pistons 32 and 33, respectively, rigidly connected by a piston rod 34, the latter extending upwardly through and having a 45 sliding fit within a head 35 suitably secured upon the upper end of the cylinder 21. The head 35 is provided with a stuffing box 36 of conventional form, designed to prevent the leakage of oil upwardly or downwardly 50 through the head, as will be understood.

For effecting rotation of the entire pump within the casing 15 for a purpose which will be hereinafter described, the piston 32 is provided with a nut 32^a adapted to engage 55 within an angular socket 23^a formed on the upper end of the connecting collar 23. The nut 32^a engages within the socket 23^a only when the piston rod is moved to its extreme lower limit or to a position below that 60 shown in Figure 1, whereby rotation of the piston rod will effect a corresponding movement of the entire pump upon the seat member 18. The nut 32^a is withdrawn from the socket 23^a when the piston rod is returned 65 to pumping position.

The head 35 is provided with a depending flange 38 to which is secured a cylindrical jacket 39 maintained in spaced parallel relation to the cylinder 21 to provide a chamber 40 which is open at its lower end and which 70 communicates at its upper end with the upper end of the cylinder through a circular series of ports 41 formed in the cylinder. The head 35 and the lower end of the jacket 39 are formed with radially extending flanges 75 42 which are circumferentially spaced, as shown in Figures 3 and 4, and which are adapted to engage the inner wall of the casing for the purpose of centering the pump as a whole upon the seat member 18. 80

In designing the pump, it is necessary for reasons to be hereinafter explained that the stroke of the pistons 32 and 33 be restricted to approximately one-half of the length of the cylinders 20 and 21 so that in the cylinder 20 below the piston 32 is provided what I term a resultant settling chamber through which the piston at no time moves during its working stroke. In the cylinder 21, the stroke of the piston 33 is such that a quantity of fluid less than the fluid capacity of the chamber 40 is ejected from the cylinder on the up stroke of the piston, while on the piston's down stroke only the same quantity of fluid is drawn into the cylinder. In this manner a second resultant settling chamber is formed between the jacket 39 and the cylinder 21, namely, the chamber 40. 85 90 95

In operation, the pump is lowered into the casing until the valve seat 24 rests on the supporting member 18, the latter having been fixed within the casing at a predetermined point which may be above or below the normal level of the oil in the casing. Assuming that the oil level is below the supporting member 18, upward movement of the piston rod 34 from the position shown in Figure 1 to that shown in Figure 2 causes the piston 32 to create a negative pressure in the cylinder 20 which first opens the intake valve 25 and then draws oil into the cylinder, filling the first resultant settling chamber hereinbefore described and the space above the chamber provided by the upward displacement of the piston, which space will be hereinafter referred to as the working chamber. During this operation the several discharge valves 29 remain closed so that oil does not pass into the chamber provided between the casing 15 and the pump barrel. However, on the down stroke of the piston rod, the piston 32 moving downwardly in the cylinder ejects the oil from the working chamber and possibly a portion of the oil filling the resultant settling chamber, the oil ejected from the working chamber passing into the valve body, closing the valve 25 and opening the valves 29, as illustrated in Figure 1, so that the oil ejected is forced upwardly through the ports 28 and into the space between the 105 110 115 120 125 130

pump barrel and casing. As indicated by the arrows in Figure 1, substantially half of the oil discharged through the ports 28 passes upwardly beyond the pump barrel and ultimately to the surface, while the remainder passes into the chamber 40 and through the ports 41 into the upper cylinder 21 to take up the upper piston displacement.

10 The succeeding up stroke of the piston 32 causes a second quantity of oil to be drawn into the lower cylinder, and with it the return of the body of oil originally occupying the resultant settling chamber so as to fill 70 the latter and thus interpose itself between the piston and the new quantity of oil drawn into the cylinder, which I term the active oil. With the up stroke of the upper piston 33, the body of oil introduced into the upper cylinder on the down stroke is forced from the cylinder into the settling chamber 40, but because of the fact that the fluid capacity of the chamber 40 exceeds the oil displaced by the piston, the original body of 75 oil is not ejected from but remains in the chamber to be returned to the cylinder on the succeeding down stroke of the piston. The oil below the original oil body in the chamber 40, which I term the active oil, is ejected from the chamber and passes upwardly between the pump barrel and casing, as indicated by the arrows in Figure 2. In this manner the original body of oil entering the upper cylinder and alternately 80 25 pumped from the settling chamber 40 to the cylinder remains at all times in interposed relation to the upper piston and active oil.

From the foregoing operation it will be clear that during reciprocation of the pistons oil will be intermittently drawn into the pump and successively elevated first by one piston and then the other and in such manner that the bodies of oil originally introduced into the settling chambers will be retained within the pump to provide lubricating and protecting fluid mediums for the pistons, and because of the fact that the fluid mediums move as bodies in the settling chambers, the solid particles or other foreign matter contained in these bodies of oil will be given ample opportunity, during reciprocation of the pistons, to settle to the bottom of the bodies so as to be ultimately discharged from the cylinders and jacket, thus insuring at all times clean fluid mediums in the working areas of the pistons whereby the pistons and cylinders are maintained free from the abrasive action of the solid particles.

60 If the positioning of the supporting member 18 in the casing is such that the pump is submerged when seated on the supporting member, the resultant settling chambers are filled with the upper strata of oil during 65 submersion as it will be understood that the

oil will be free to pass into both cylinders. As the upper strata of oil is usually clean, that is, free from solid particles or other foreign matter, the oil filling the settling chambers will likewise be clean, and maintained clean by virtue of their bodily movements, as has been described.

Should the pump be used in a well bearing oil which is supersaturated with solid particles, clean oil can be supplied to the settling chambers by forming the piston rod 34 with a duct 34^a extending completely through the rod so that its lower end is in communication with the settling chamber of the lower cylinder. To place the duct in 80 communication with the upper cylinder so that oil can be supplied to the upper settling chamber 40, a port 34^b is formed in the rod, as shown. By this construction oil introduced into the duct at the top of the well 85 will flow into and fill the cylinders to subsequently provide the clean fluid mediums.

It is to be particularly noted that the discharge and intake valves 25 and 29 are arranged in close proximity to each other, and 90 in the area adjacent these valves the oil is continuously active so that the solid particles contained in the oil are at all times held in suspension, and it has been found in practice that they are held in suspension 95 in the same ratio as when drawn into the pump, thereby preventing the accumulation of solid matter in the pump and insuring its proper operation at all times.

Should the pump be inactive for a time 100 sufficient to allow solid matter to settle and thus prevent proper operation of any of the valves 25 and 29, the pump as a unit can be raised from its seat to allow the oil in the casing to be discharged through the port 19, 105 thereby flushing out all solid matter so that the valves are free to operate in the manner intended. Should solid matter accumulate upon the supporting member 19 so as to prevent the proper seating of the member 110 24 thereon the piston rod 34 can be moved downwardly to cause the nut 32^a to engage within the angular socket 23^a whereby, upon rotation of the piston rod, the entire pump is rotated to dislodge the solid matter from 115 the supporting member so that the member 24 can be properly seated thereon. If it is found necessary to repair any parts of the pump, the entire pump body can be readily removed from the casing without disturbing 120 the casing or the supporting member 18, and it is to be noted that as soon as the withdrawal of the pump is started the port 19 will be opened to allow the casing to be emptied.

Although I have herein shown and described only one form of fluid pump embodying my invention, it is to be understood that various changes and modifications may be made herein without departing from the 125 130

spirit of the invention and the spirit and scope of the appended claims.

What I claim is:

1. A fluid pump comprising a pair of pistons, a barrel in which said pistons are adapted to work, said barrel being adapted to be lowered into an oil string casing so as to be submerged in the static oil of a well, both ends of said barrel being open to allow the upper strata of oil to enter the ends of the barrel and provide fluid mediums free from solid particles in which said pistons are adapted to work, and means adapted to co-operate with said oil string casing for elevating oil on each stroke of the pistons and in such manner as to prevent complete expulsion of the fluid mediums from the barrel.
2. A fluid pump as embodied in claim 1, wherein said means comprises a jacket surrounding the upper end of the barrel to provide a chamber between the two in which the fluid medium in the upper end of the barrel is adapted to circulate when the upper piston is operating, an intake valve at the lower end of the barrel adapted to be opened only on the up stroke of the lower piston to admit oil to the barrel, and a discharge valve adapted to be opened only on the down stroke of the pistons to discharge the oil expelled from the lower end of the barrel to a point between the barrel and casing.
3. A fluid pump comprising a barrel having an upper cylinder and a lower cylinder of greater internal area than the upper barrel, connected pistons reciprocable in the cylinders and the strokes of which are less than the length of the cylinders so as to provide a settling chamber in one cylinder in which the corresponding piston does not move, a jacket surrounding the upper cylinder and having its lower end open, said jacket being spaced from the cylinder to provide a settling chamber between the two, ports in the upper cylinder providing communication between the chamber and cylinder, a valve body at the lower end of the lower cylinder, an intake port in the valve body, discharge ports in the valve body, and valves controlling said ports in the manner and for the purpose described.
4. A fluid pump comprising a barrel adapted to be submerged in a fluid to be elevated and having a chamber therein adapted to be partly filled with the fluid during submersion, a piston operating in the barrel in such manner that the fluid in the chamber provides a fluid medium between the piston

and the oil elevated, and valves controlling the circulation of fluid into and out of the barrel in such manner that the fluid medium is retained in the chamber and moves as a body under the action of the piston so as to allow solid matter therein to settle to the bottom of the body for ultimate discharge from the barrel.

5. A fluid pump comprising a barrel having chambers in the opposite ends thereof adapted to be partly filled with a fluid, pistons operating in the chambers in such manner that the fluid in the chamber provides permanent fluid mediums between the pistons and the fluid elevated, valve ports for controlling the circulation of fluid elevated by one piston to deliver such fluid to a point between the barrel and casing, and without allowing discharge of the corresponding fluid medium from the corresponding chamber, and means associated with the barrel for causing the other piston to further elevate a portion of the fluid elevated by the first piston through the actuation of the corresponding fluid medium and maintaining the corresponding fluid medium in interposed relation to the piston and fluid elevated.

6. In a fluid pump, a barrel having its lower end open, a valve body supported on and communicating with the lower end of the barrel, an intake valved port in the valve body, a discharge valved port in the valve body, and a piston reciprocable in the barrel to open the intake port for drawing fluid into the valve body on its upstroke and to close the intake port and open the discharge port on its down stroke whereby the fluid drawn into the valve body is expelled from the body through the discharge port, the intake port being adapted to be opened when submerging the barrel into a fluid so that a portion of the fluid is admitted to the barrel and the stroke of the piston is less than the length of the barrel so that fluid admitted to the barrel during submersion remains in the barrel and forms a fluid medium between the piston and fluid subsequently elevated by the piston.

7. In a fluid pump for wells, a barrel, means adapted to support the barrel at a predetermined level in a casing, a valve body on the barrel having a member adapted to seat on said means, and a piston in the barrel and movable to a position in which it is locked to the valve body whereby rotation of the body and member can be effected for the purpose described.

CHARLES VAN AMBURGH.
